TWIN SOLE-LAYING PRESS

Otto Michalk, Freital, near Dresden, Germany

Application July 27, 1932, Serial No. 625,077, and
in Germany August 3, 1931

5 Claims. (Cl. 12—36)

In the known twin and multiple sole laying presses strong rubber rests with springs are used as pressing means, these rests being employed in connection with normal pressing 5 moulds for all sorts of foot-wear and all trusses of the joints, in consequence whereof an adaptation of the sole to the shape of the last is not warranted. Besides, those twin sole laying presses which are operated with toggle-joint 10 levers or with spindles suffer from the drawback that the time during which the sole is pressed against the rubber pressing pad is too short, because the shoe that is attached to the last is pressed on only in the highest position of the 15 revolution while the machine is being driven.

In order to obviate the above-mentioned drawbacks it had been proposed to make use of air-pressure sticking presses for the laying of the soles, said presses operating, for instance, in 20 connection with a rotary table, but with the presses the shoe can be removed from the pressing mould only after the table has performed a complete revolution. This manner of working is too slow for an economical manufacture of 25 shoes. Especially with welt sewn shoes, as chiefly manufactured to-day it would be necessary to lay the soles of the shoes and to remove them from the press in the same rate of time as with the high-speed sole cutting machine.

30 The twin sole laying press forming the subject-matter of the present invention responds to all requirements in that by the closing pressure exerted by the compressed air in the clamping device of the one press the clamping device of the other press is relieved and reversely. It is suited to the purpose to equip the machine with a foot valve and a change-over valve, the operation being then this that by the foot valve not only the clamping device is in steps subjected to 35 pressure, but also the air pad is subjected to pressure across the change-over valve, and the tensioning device of the neighbouring laying place is relieved whereby at the same time the further advantage is attained that the operator 40 can freely make use of both his hands and the work can be carried out in a continuous manner.

A sole laying press improved according to this invention is illustrated diagrammatically and by way of example on the accompanying drawings on which

Figure 1 is a side-view of the same, also the pressing cylinder and the foot valve being shown in this figure.

Figure 2 is a plan of the press.

Figure 3 is a vertical section through the foot

valve, this figure being drawn to a greatly enlarged scale relatively to Figs. 1 and 2.

Figure 4 is a plan of the foot-valve, also drawn to that enlarged scale.

Figures 5 and 6 are views similar to Fig. 3, 60 showing two other positions of the foot-valve.

Figure 7 is a side-view of the clamping-in device, this figure being also drawn to an enlarged scale relatively to Figs. 1 and 2.

Figure 8 is a rear-view of the clamping-in 65 device.

Figure 9 is a horizontal longitudinal section through a twin-valve for reversing the action of the air at the pressing places, also this figure being drawn to a greatly enlarged scale; and 70

Figure 10 is a vertical longitudinal section through the valve shown in Fig. 9, all as fully described hereinafter.

On the drawings, *a* (Fig. 1) is a standard, 75 from the top of which project forwardly, about in the height of the plate of a table, two pneumatic pressing moulds, each consisting of a pressing pad 8 (Fig. 1), an abutment support 8' and a clamping device 7, to which pertains a double-armed lever 7' which is supported at the point 7'' and the rear arm of which can be actuated by a head-member 6''. At the rear side of the standard *a* is a compressed-air cylinder 6, in which is a piston 6', the rod of which bears 80 on its top said member 6''. The cylinder 6 can be supplied with compressed air, and can also be relieved from the pressure of the same, by means of the foot valve 1 by the intermediary of the pipes 4 and 5. The compressed air is contained in a receptacle 3' which is connected 85 with the foot-valve 1 through the pipe 3.

Two such pressing devices are arranged side by side, as appears from Fig. 2.

The foot valve is actuated by means of a 90 plunger 2' (Figs. 3, 5 and 6) having on its projecting top a foot knob 2 which is held in its uppermost position by a helical compression spring 2'' (Fig. 3). Inside the lower part of this spring is another helical compression spring 2^a which is compressed, however, only after the spring 2'' has been compressed in a certain measure, as appears from Figs. 5 and 6. When the plunger 2' is in the position shown in Fig. 3, the pipe or 95 passage 3 does not communicate either with the pipe 4 or with the pipe 5. In the position shown in Fig. 5 the passage 3 communicates with the pipe 4, and in the position shown in Fig. 6 the passage 3 communicates with the pipe 5. In 100 Fig. 5 only the spring 2'' has been compressed, and in Fig. 6 the spring 2^a has been compressed, 105 110

too. The two springs are, thus, compressed one after the other. In order to render possible establishing said communications, the plunger 2' is provided with two circumferential grooves *b* and *c* (Figs. 3, 5 and 6), and its lower end is provided with an abutment member *d* limiting the upward stroke of the plunger.

Between the two pressing places is a twin or change-over valve 12 (Figs. 9 and 10) having two plungers 13 and 14 which are controlled by the head members 6" of the piston rods of the compressed-air cylinders 6, as well as by cams 6^a, and also by pawls 15 which are subjected to the pressure of plate springs 16. The valve 12 is connected with an air-cylinder 11 (Figs. 7 and 8) through a pipe 17. The cylinder 11 is attached to the lever 7'. As there are two pressing places, there are, of course, two sets of the mechanisms described in this paragraph.

20 Release of the clamping device is effected by the piston 11' of the air cylinder 11 which withdraws a pawl 9 from a ratchet rack 10 whereby the lever 7' is permitted to return into its position of rest which is that shown in dotted lines in Fig. 1.

25 The manner of operation of the valve 12 is as follows:

When the shoe has been placed into the press in order to have its sole shaped, first the foot knob 2 is depressed counter to the pressure of the spring 2^a until the counter-pressure of the spring 2^a becomes perceptible (Fig. 5). In this position of the plunger 2' the circumferential groove *b* establishes a communication between the pipes 3 and 4, so that the compressed air can flow through the pressure reducing valve 4' (Fig. 1) into the air cylinder 6, whereupon the now lifted head member 6" effects closing of the clamping device 7 with a certain moderate pressure by the intermediary of the lever 7'.

30 When the knob 2 is further depressed, also the counter-pressure of the spring 2^a is overcome and the position of the plunger is now such that the pressure pipe 3 communicates with the pipe 5 by the intermediary of the annular groove *b*, the compressed air flowing now from the receptacle 3' to the cylinder 6 whereby the piston in this cylinder is lifted, as is, therefore, also the head 6", and the shoe located upon the last will 35 now be firmly pressed upon the pad 8. The last with the shoe thereon is automatically retained in this position by the pawl 9 and the ratchet rack 10 (Fig. 7). When thereafter the foot is removed from the knob 2 this latter is automatically lifted by the spring 2^a so that the plunger 2' is moved back into its original position (Fig. 3) in which the annular groove *b* connects the pipe 5 with the blow-off channel 5', through which the air escapes from the cylinder, and also the members 6' and 6" re-assume now their position of rest which is that shown in Fig. 1.

35 Each piston-rod head 6" co-operates with the twin valve 12 (Figs. 9 and 10). The compressed air is conducted to this valve from the air receptacle 3' through the pipe 19 (Fig. 7). When the left-hand head 6" rises into its highest position, its cam 6^a shifts the plunger 14 to the right and the pawl 15 moves past the plunger 13 without actuating it (Fig. 10). The pipes 20 and 21 conduct the compressed air to the two adjacent pressing pads. The annular groove *e* of the plunger 14 connects then the pipes 20 and 17 with the blow-out hole 24 whereby the adjacent pad 8 and the appertaining pressure cylinder 11 are emptied. The pawl 9 engages the ap-

pertaining ratchet rack 10 whereby the shoe located upon the pressing pad is retained thereon.

When the plunger 6' gets back into its former position, as already described, the left-hand pawl 15 presses the plunger 13 to the right (Fig. 10) whereby the annular groove *f* of this plunger establishes a communication between the pipe 19 and the pipes 21 and 17'. Owing thereto, the air flows into the pressing pad and into the air cylinder of the other pressing place. The piston 11' of the cylinder 11 will now be shifted and will lift the pawl 9 off from the ratchet rack 10 so that the lever 7 is disengaged (Fig. 7). The respective pressing place is now freely accessible and the shoe can be removed therefrom.

90 The effects obtained by the above-described air valve control are, thus, the following:

Firstly, the shoe is, by depressing the foot knob 2, clamped fast by compressed air at the pressing place, is locked in its position, and at the same time the other pressing place is relieved from the action of the compressed air, and

95 Secondly, when the foot is withdrawn from the foot knob the pad of the other pressing place is filled with the compressed air and the clamping device of the first pressing place is released.

100 These procedures are continually repeated. When the foot knob is again depressed, the members of the second pressing place are actuated in the described manner, and so on, alternately. When a shoe has been clamped fast at the right-hand pressing place, that at the left-hand is released, and this alternating procedure is continued.

105 Finally I mention that an air cock 23 (Figs. 7 and 8) is inserted into the pipe 20 and into the pipe 21 whereby it is rendered possible to let the compressed air escape at once from the one or the other pressing pad so that the sole can be shifted in case it should have been put on in an 110 improper position.

I claim:

1. A twin sole laying press, comprising, in combination with pneumatic pressing pads, and with pneumatic means for clamping the last with the shoe thereon fast upon the sole located upon the pneumatic pressing pad, means for controlling the supply of the compressed air to, and its discharge from, said pads and their clamping means in such a manner that one of said pads 110 and its clamping means are supplied with the compressed air and at the same time the other pad and its clamping means are liberated from the compressed air, and reversely.

115 2. A twin sole laying press, comprising, in combination with pneumatic pressing pads, and with pneumatic means for clamping the last with the shoe thereon fast upon the sole located upon the pneumatic pressing pad, a reversing compressed-air valve arranged between the two 120 pressing devices, a compressed-air cylinder at each pressing device, a piston and a piston rod in each cylinder, and cams provided on said rods, said reversing valve and said cams being so arranged with respect to one another as to be 125 adapted to reverse said valve in such a manner that one of said pads and its clamping means are supplied with the compressed air and at the same time the other pad and its clamping means are liberated from the compressed air, and reversely.

130 3. A twin sole laying press, comprising, in combination with pneumatic pressing pads, and with pneumatic means for clamping the last with the shoe thereon fast upon the sole located upon 135

the pneumatic pressing pad, means for controlling the supply of the compressed air to, and its discharge from, said pads and their clamping means in such a manner that one thereof is supplied with the compressed air and at the same time the other pad and its clamping means are liberated from the compressed air, and reversely, a pressure reducing valve inserted into the compressed-air supply conduit to said clamping means, and a valve so arranged as to be adapted to be actuated by a foot of the operator and so designed that the appertaining clamping means is subjected in steps to the pressure of the air.

4. A twin sole laying press, comprising, in combination with pneumatic pressing pads, and with pneumatic means for clamping the last with the shoe thereon fast upon the sole located upon the pneumatic pressing pad, a compressed-air valve so arranged as to be adapted to be actuated by a foot of the operator and so designed that it

controls the supply of the compressed air to one of said pads and its clamping means and controls at the same time the discharge of the compressed air from the other pad and its clamping means, and reversely.

5. A twin sole laying press, comprising, in combination with pneumatic pressing pads, and with pneumatic means for clamping the last with the shoe thereon fast upon the sole located upon the pneumatic pressing pad, a compressed-air valve so arranged as to be adapted to be actuated by a foot of the operator and so designed that it controls the supply of the compressed air to one of said pads and its clamping means and controls at the same time the discharge of the compressed air from the other pad and its clamping means, and reversely, and a pressure reducing valve inserted into the compressed-air supply to said clamping means.
